CLAIM

The ornamental design for a bottle, as shown and described.

DESCRIPTION

FIG. 1 is a perspective view of a bottle showing our new design;

FIG. 2 is a front elevational view of the bottle depicted in FIG. 1, the opposite rear elevational view being a mirror image thereof;

FIG. 3 is a first side elevational view of the bottle depicted in FIG. 2;

FIG. 4 is a second side elevational view of the bottle depicted in FIG. 2, said second side elevational view being opposite the first side elevational view depicted in FIG. 3; FIG. 5 is a top plan view of the bottle depicted in FIG. 2; FIG. 6 is a bottom plan view of the bottle depicted in FIG. 2;

FIG. 7 is a perspective view of a second embodiment of the bottle depicted in FIG. 1;

FIG. 8 is a front elevational view of the bottle depicted in FIG. 7, the opposite rear elevational view being a mirror image thereof;

FIG. 9 is a first side elevational view of the bottle depicted in FIG. 7;

FIG. 10 is a second side elevational view of the bottle depicted in FIG. 7, said second side elevational view being opposite the first side elevational view depicted in FIG. 9; FIG. 11 is a top plan view of the bottle depicted in FIG. 7; and,

FIG. 12 is a bottom plan view of the bottle depicted in FIG. 7.

The broken line environmental showing is for illustrative purposes only and does not form part of the claimed design.
